UNITED STATES PATENT OFFICE.

JAMES D. RANDALL, OF CINCINNATI, OHIO, ASSIGNOR TO THE J. D. RANDALL COMPANY, OF CINCINNATI, OHIO, A CORPORATION OF OHIO.

THREAD LOCKING AND RELEASING DEVICE FOR SEWING-MACHINES.

1,237,555.

Specification of Letters Patent. Patented Aug. 21, 1917.

Application filed December 16, 1915. Serial No. 67,155.

To all whom it may concern:

Be it known that I, JAMES D. RANDALL, a citizen of the United States of America, and resident of Cincinnati, county of Hamilton, State of Ohio, have invented certain new and useful Improvements in Thread Locking and Releasing Devices for Sewing-Machines, of which the following is a specification.

10 This invention relates to improvements in thread tension devices for sewing machines of the type disclosed in United States Letters Patent No. 388,752, issued to George Amborn on August 28, 1888.

15 In sewing machines of the type disclosed in said Letters Patent, the thread is locked by the front and rear thread-brakes 4 and 5, while the take-up 22 and 23 is operating, and while the thread is being drawn forward by the needle, said thread brakes are open. When the operator desires to drop a stitch, he stops the machine and draws enough thread forward to enable him to drop the stitch. Unless he stops the machine 25 at the period at which the thread-brakes are open, he must move the driven pulley by hand, until the thread-brakes are open. This wastes much of the operator's time.

It is therefore an object of my invention 30 to produce a thread releasing device which will release the thread and permit the operator to shift the goods under the foot of the machine, the desired distance without having to touch the thread, thereby eliminating 35 the liability of waste of thread through the ordinary operation of drop stitching.

A further object of my thread releasing device is to place the device under control of the operator without having to take the 40 operator's attention and hands from the work being done.

These and other objects are attained in the device described in the following specification and illustrated in the accompanying 45 drawings in which;

Figure 1 is a fragmental elevation of the upper portion of a sewing machine constructed for sewing heavy materials such as leather, having a tension releasing device 50 embodying my invention attached thereto.

Fig. 2 is a fragmental perspective view of a section of belting having a portion thereof drop stitched, to illustrate the work done by my improved construction.

55 Fig. 3 is a view similar to that of Fig.

2, but illustrating the work ordinarily done in drop stitching operations.

In sewing machines of the type disclosed in the above mentioned patent, employed in the stitching of harness and similar heavy 60 materials, two thread locking devices 4 and 5 are employed, each of these devices consisting of front and rear thread brakes 6 and 7 pivotally mounted on pins 8 and 9 extending from a bracket 10 mounted on the top 65 of the frame 11 of the machine, and brake blocks 12 and 13 against which the brakes 6 and 7 bear. On the opposite sides of the brakes, arms 14 and 15 are formed, these arms being under tension by means of coiled 70 springs 16 and 17 adapted to retain the brakes 6 and 7 in engagement with the blocks 12 and 13. In order to prevent displacement of the thread from the blocks and brakes, a guide 19 is provided between the 75 blocks and secured to the bracket 10, while on the opposite sides of the blocks and brakes, the thread is passed through eyelets 20 and 21 formed as integral parts of the arms 14 and 15 of the brakes 6 and 7. 80 The usual take-up, consisting of the reciprocating pulleys 22 and 23, is employed for taking up the thread carried forward by the needle.

In order to release the clamping action of 85 the brakes 6 and 7 upon the blocks 12 and 13, I employ the following described mechanism. Pivotally mounted at a point 25 on a bracket 26 mounted on the frame 11, is a lever 27 which in said Amborn Patent No. 90 388,752, is adapted to raise the presser foot. I provide the forward end of this lever with a pin 28 which operates in a slot 29 formed in the bracket 10. This pin engages a cam 30 and is adapted to cause rotation of the 95 cam upon its pivot pin 31, by riding over the cam surface 32 when the lever 27 is operated to move the pin upwardly through the slot 29. This oscillatory movement of the cam is communicated to the arms 14 and 100 15 of the brakes 6 and 7 to lift the brakes from the blocks 12 and 13 and thereby release the thread, the means for communicating this motion to the arm 14 consisting of a stud 33 reciprocally mounted in bearing 105 lugs 34 mounted on the bracket 10, and which engages the under side of the arm 14 and the upper side of a finger 35 of the cam 30. The arm 15 of the brake 7 receives motion from the cam 30 by means of a lever 36 110

pivottally mounted on a pin 37 in the bracket 10, the forward end of the lever having a tooth 38 engaging a recess 39 of the cam 30 for operation therewith. The rearwardly 5 extending arm 40 of the lever 36 engages the under side of the arm 15 of the brake 7.

Thus when the pin 28 is moved upwardly in the slot 29 to cause the cam 30 to rotate upon the pin 31, the stud 33 and consequently the arm 14 of the brake 6, are raised, as are also the arm 40 of the lever 36 and the arm 15 of the brake 7 because of the engagement of the tooth 38 and the recess 39 formed in the cam 30. This operation causes simultaneous releasing of the thread at both thread brakes and permits of its being drawn so freely from its source of supply and from the needle at the foot of the machine, that the shifting of the work to which the thread is attached pulls out the thread as the work is shifted to the point at which the stitching is again started. Operation of the lever 27 which carries the pin 28 is caused by a rod 41 which is connected with the rear end of the lever and which is operated by a foot treadle convenient to the operator. The lever 27 is maintained in its normal position with the pin 28 at the bottom of the slot 29, by means of a coiled spring 42 secured thereto at one end and to an arm 43 of the bracket 26 at its opposite end.

Having thus described my invention, what I claim is;

35 1. A thread releasing device for sewing machines, comprising a block, a brake adapted to clamp a thread between it and the block, an arm formed on the brake adapted to be moved to lift the brake from the block to release the thread, a spring attached to the arm and normally holding the brake in yielding engagement with the

block to clamp the thread between the brake and the block, a cam pivotally mounted adjacent to the brake and operatively connected therewith, and a lever operatively connected with the cam for causing the cam to lift the brake to release the thread. 45

2. In a thread releasing device for sewing machines, the combination of a block, a brake adapted to clamp a thread between it and the block, an arm formed on the brake and adapted to be moved to lift the brake from the block to release the thread, a spring attached to the arm and normally holding the brake in yielding engagement with the block to clamp the thread between the brake and the block, a second block spaced from the first mentioned block, a second brake spaced from the first mentioned brake and adapted to clamp the thread passing from the first mentioned brake and block, between it and the second mentioned block, an arm formed on the second mentioned brake and adapted to be moved to lift the brake from the block to release the thread, a spring attached to the arm and normally holding the second mentioned brake in engagement with the second mentioned block to clamp the thread between the second mentioned brake and the second mentioned block, a cam pivotally mounted adjacent to the brakes and operatively connected therewith, and a lever operatively connected with the cam for causing simultaneous releasing movement of the brakes when the lever is operated. 55

In testimony whereof, I have hereunto subscribed my name this 13th day of December, 1915.

JAMES D. RANDALL.
